UNITED STATES PATENT OFFICE.

EARL V. COULSTON, OF CLEVELAND, OHIO.

STOVE.

1,152,793.

Specification of Letters Patent.

Patented Sept. 7, 1915.

Application filed January 4, 1913. Serial No. 740,182.

To all whom it may concern:

Be it known that I, EARL V. COULSTON, a citizen of the United States, resident of Cleveland, county of Cuyahoga, and State of Ohio, have invented a new and useful Improvement in Stoves, of which the following is a specification, the principle of the invention being herein explained and the best mode in which I have contemplated applying that principle, so as to distinguish it from other inventions.

My invention relates to stoves and particularly that type of stove which is adapted for use either as a coal stove or a gas stove.

The object of the invention is to combine in one structure the two above named types of stoves in the most economical and efficient manner.

As is well known to those skilled in the art, great care must be exercised in designing a stove and especially in so far as concerns the upper flue or duct leading from the fire box, in order to obtain the most favorable conditions for maintaining the proper draft.

A specific object of my invention therefore, is to combine a coal burning with a gas burning stove in such a manner as to permit of the proper cross-sectional area of the ducts, also at the same time refrain from increasing unnecessarily the horizontal dimensions of the stove, and furthermore to combine a maximum number of gas stove holes with the coal stove holes.

The said invention consists of means hereinafter fully described and particularly set forth in the claims.

The annexed drawings and the following description set forth in detail certain means embodying my invention, the disclosed means, however, constituting but one of various mechanical forms in which the principle of the invention may be applied.

In said annexed drawings:—Figure 1 represents a plan of a stove embodying my invention, in which the lids and other removable parts of the top plate are shown removed. Fig. 2 represents a vertical, fragmentary transverse section taken upon the plane indicated by line II—II in Fig. 1. Fig. 3 represents a vertical longitudinal section of the stove taken upon the plane indicated by line III—III of Fig. 1.

The illustrated embodiment of my invention comprises a main frame A in which is suitably mounted the oven B, Fig. 3, at one

side of which latter is provided the fire-box C. The general structure in so far as concerns the above named elements forms no part of my present invention and a further description thereof will therefore be omitted.

Leading from the upper portion of the fire-box, above the oven and below the upper portion of the main frame is a duct D, substantially co-extensive with that part of the horizontal cross-sectional area of the stove exclusive of the firebox. In the rear wall of the main frame is an opening a which communicates with the inlet opening e of one of two branches e' of a main outlet-flue E by means of a short intermediate duct a', as shown in Fig. 1. This opening a which is limited on the right-hand side by a short wall e⁵, Fig. 1, extending into the duct D, may be opened or closed at will by means of a sliding damper F to which is suitably secured a rod f having a handle f' projecting above the upper surface of the stove through a suitable slot f², whereby said damper may, in the usual manner, be manipulated from the exterior. It will be seen therefore that the products of combustion emanating from the fire-box may, when the damper is open, pass through the duct D through the opening a, duct a' and thus out through the flue E, and when said damper is closed communication between the latter and said duct D is interrupted.

Suitable apertures a² a² and lids a³ a³ are provided in the usual manner, said openings communicating directly with the firebox and with the duct D, whereby the products of combustion may be applied to the utensils which it is desired to heat. Also as in the ordinary stove all of the upper surface of the stove adjacent to the said duct D and fire-box is heated in the usual manner.

In addition to the apertures a², there are provided additional apertures a⁴ a⁴ in the top plate of the main frame. In the illustrated example four of these apertures are provided and suitable lids a⁵ are supplied for closing same when desired, in the usual manner. Below each of these latter apertures is placed a gas burner G, shown in Fig. 1. These burners are connected in the usual manner by means of suitable pipes with a source of gas supply, the introduction of the gas being controlled by the usual valves g g. These burners are surrounded by partitions h² forming a chamber H whose

walls project into the duct D as shown in Figs. 2 and 3. This chamber H communicates at h with a duct h' formed by walls h^3 depending from the upper part of the stove 5 and separating said duct h' from the duct D, the walls h^2 of chamber H being cut away to the desired extent at this point for the purpose of such communication. Duct h' communicates with the inlet opening e^2 , 10 Fig. 1, of a second branch e^3 of the outlet flue E. The bottom of said chamber H rests upon the top of the oven B. A damper e^4 is placed in the latter whereby communication therethrough may be interrupted, as 15 will be understood. The partitions forming this separate chamber are all formed by one single integral structure which depends from the top plate and is permanently secured with reference thereto in any suitable and 20 accepted manner.

It will be noted from the above description and from the drawings that the chamber H consists of two parts, the right-hand part which extends parallel with the right-hand side of the stove and a central part which projects at right-angles with said first-named part and in a direction opposite that of the movement of the gases of combustion from the fire-box C through the duct 25 D and which divides the major portion of the latter into two branches. The first part of said chamber contains two gas burners and the second part likewise two gas burners. In order to interfere with the passage 30 of the gas through the duct D to the least possible extent, the left-hand ends of the walls h^2 of the second-named part of the chamber H converge, as shown by the dotted lines in Fig. 1. As also shown, these walls 35 lie between the two right-hand coal stove holes a^2 and hence do not interfere with the function of the latter.

It will be noted also that the chamber H extends only partly beyond the right-hand 40 end of the vertical walls A' of the main frame of the stove, the major portion of the chamber extending into the said duct D. The right-hand end of this latter duct is formed by the bottom of the chamber H and 45 by a beveled portion B' of the upper walls of the oven B, as shown in Fig. 3. This forms a short downwardly inclined portion of said duct D which communicates with the down flue N formed between the right-hand 50 wall A' of the stove and the oven, the bottom of this flue communicating with the horizontal flue N' which communicates with the up flue L² by means of an opening n, the upper end of flue L² communicating with 55 the branch e' of the main flue E, as shown. The left-hand end of the flue or duct D increases in vertical dimension from the outlet-opening e of the fire-box toward the right, as shown in Fig. 1, such result being obtained by the use of a downwardly in-

clined casting B² forming the bottom of the left-hand end of said duct. By such construction and the increase of area of the right-hand end of duct D effected by the use of the beveled corner of the oven, I obtain 70 a cross-sectional area of duct D uniform throughout and I make such area substantially equal to the area of opening e.

Formed integrally with the depending walls h^2 of said chamber, and upon the interior thereof is a ledge h^6 upon which rests a removable horizontal partition consisting of two separable plates h^4 and h^5 , which divides the said chamber into an upper and a lower compartment. The lower compartment communicates with the atmosphere by means of an opening h^7 , Fig. 3, atmospheric air being thus supplied for the combustion of the gas discharged from the burners. The plates h^4 and h^5 are provided with openings h^8 immediately above the burners whereby the gas may be discharged into the upper compartment, a sufficient space being left between the burner and the sides of the opening to admit of a proper quantity of 85 air for combustion purposes. The plate h^5 is formed with an upwardly projecting portion h^9 , Figs. 1 and 3, which forms a part of the surrounding walls of the chamber H. This portion h^9 is used in this particular instance in order to provide a less direct discharge of gases of combustion into the duct h' from that portion of the chamber H immediately adjacent to the opening h . This portion is furthermore made a part of the removable plate h^5 so that upon the removal of the latter the opening into duct h' may be correspondingly enlarged so as to facilitate access thereto for cleaning or other purposes, it being apparent from the construction, as 90 shown in Fig. 1, that such removal of portion h^9 removes any angles in the duct h' from which it might be difficult to remove dirt or other deposits.

The other two burners which are located 11 nearest the opening h are provided with deflectors h^{10} which are interposed between the combustion zones thereof and said openings. These deflectors consist of upwardly projecting lugs cast integrally with the plate h^4 11 and cause the products of combustion to take a devious path in their travel toward the opening h , thus contributing to the conservation of the heat contained in such products 12 in their application for heating purposes, as will be readily understood.

From the above construction it will be noted that that portion of the stove's interior which immediately surrounds the gas burners is completely separated from that portion which is traversed by the products of combustion from the fire-box C. The gas burners are therefore protected against any deleterious action which such products of combustion might otherwise exert by their 13

immediate contact with same, and a longer life of said burners is thereby assured. In addition protection is thus afforded against the clogging of the gas apertures in the 5 burners from the soot and other solid particles contained in said gases of combustion. When the fire-box is in use the damper e^4 is placed in its closing position so as not to offer any inducement for the gases from said 10 fire-box to enter into the chamber H through any crevices that necessarily may exist in its walls. When the fire-box is not in use and the gas burners are, then the opening a is closed by means of the damper F.

15 I am fully aware that combined coal and gas burning stoves in which inclosed chambers located in the top flues and containing gas burners have been used, but heretofore, the construction and arrangement of the 20 parts of these stove tops have been such as to materially interfere with the proper operation thereof and particularly in so far as concerned the passage of the gases of combustion from the fire-box. These difficulties 25 have presented themselves particularly in connection with the upper horizontal flue leading directly from the fire-box for the reason that it is necessary in making a combined coal and gas burning stove to have the 30 gas burners and the chamber surrounding same at the top of the stove and hence necessarily in the same horizontal plane with the said flue. In these prior constructions the combination of these two fuels either resulted 35 first in the extending the stove laterally to such a distance as permitted the chamber surrounding the gas burners to be entirely removed from the passage of the gases of combustion from the fire-box; or second, in 40 restricting the cross-sectional area of the upper draft flue or passage; or third, in the formation of enlarged spaces increasing at such points the cross-sectional area of such flue or passage.

45 In the first-described construction and where the said chamber was entirely removed from the path of the gases, the result was an objectionably long stove, taking up valuable room, a characteristic which was 50 objectionable particularly from the fact that owing to the restricted size of the modern kitchen the taking up of such room was found to be a disadvantage. In the second-described construction the cross-sectional 55 area of the flue or passage was so reduced at points as to decrease the draft and thus interfere with the proper functioning of the stove. In the third-described construction a similar impeding of the draft resulted 60 from the formation of eddies and adverse currents in the enlarged portions or pools.

In my improved construction it will be noted that the chamber surrounding the gas burners extends into the upper flue or passage and directly in the passage of the gases 65

but the proper cross-sectional area of such passage at that point which would be otherwise obstructed by so placing said chamber, being, however, preserved by beveling or inclining the top of the oven.

70

In addition to the above, by dividing the gas burner chamber into two parts as previously described, one of said parts being comparatively narrow and extending same in the direction toward the fire-box and between 75 the left-hand two coal stove holes, I am enabled to provide two additional gas stove holes without interfering with the functioning of the adjacent coal stove holes. The obstruction of the left-hand end of the said 80 chamber to the flow of the gases of combustion through the upper flue or passage is reduced to a minimum by converging the walls of this part of this chamber, as has been previously described.

85

It has been found from practical experience that a given fire-box requires an outlet for its gases of combustion of a given cross-sectional area, and the flues or passages leading from this opening and for conducting 90 away the gases of combustion should be uniformly of cross-sectional area substantially equal to the area of this opening. By adopting the location of the gas burner chamber as I have described it, imparting 95 to the upper part of the oven the beveled or inclined structure so as to give the right-hand end of duct D the required area, by increasing the height of the left hand end by means of the inclined bottom-member B; 100 it will be readily seen that the vertical dimensions of the upper flue or passage D may be made such as to produce said uniformity of cross-sectional area, the amount of beveling being made such as to compensate 105 for the space occupied by the gas burner chamber at the right-hand end of the upper flue or passage. Of course there is no difficulty in connection with the remaining flues or passages of the stove inasmuch as these 110 are ordinarily so located that the above-described difficulties are not met.

By means of the above-described novel construction and arrangement of parts I am enabled to construct a stove having four gas 115 cooking openings and an equal number of coal fire cooking openings all permanently in the stove regardless of whether gas or coal is being used simultaneously or separately, without interference of any kind with each others' functions and without moving any of the parts. This full complement of cooking holes is provided without unduly increasing the dimensions of the stove and thus saving room as previously 120 described.

Having fully described my invention, what I claim and desire to secure by Letters Patent is:—

1. In a combined coal and gas stove, the 125

combination of an upper space; a fire-box; outlet flues; a chamber containing gas burners and projecting into said space; another part of said space forming a duct connecting 5 said fire-box and flues and adjacent to said chamber; a part of the latter extending transversely of said space at one end thereof and another part of said chamber extending longitudinally toward said fire-box; that 10 part of said duct adjacent to said transversely extending chamber part being downwardly inclined; the end of such chamber part which extends toward said fire-box decreasing in cross-sectional area as it approaches same; that part of said duct adjacent to such varying chamber-end increasing 15 in depth as it recedes from the fire-box; whereby the cross-sectional area of said duct is maintained substantially constant. 20

2. In a combined coal and gas stove, the combination of an upper space; a fire-box;

outlet flues; a chamber containing gas burners and projecting into said space; said chamber comprising a transverse and a longitudinal portion, said transverse portion being located at the end of the stove opposite the fire-box and the longitudinal portion projecting toward the latter; another portion of said space forming a duct connecting 25 said fire-box and outlet flues and adjacent to said chamber; a dimension of that part of said duct adjacent to such parts of said chamber as are of different cross-sectional area varying in accordance with such 30 change of area; whereby the cross-sectional area of said duct is maintained substantially constant.

Signed by me, this 2nd day of January, 1913.

EARL V. COULSTON.
